LATCH MECHANISM

Frank H. Rogers, Estancia, N. Mex.

Application April 26, 1943, Serial No. 484,627

8 Claims. (Cl. 292—332)

This invention relates to a latch mechanism and has relation more particularly to a mechanism of this kind especially designed and adapted for use in connection with a sliding door, and it is an object of the invention to provide a mechanism of this kind including a pin swingingly carried by the door, with means carried by the door for holding the pin in such position as to readily engage a keeper member positioned upon a wall adjacent to the door opening, together with further means for holding said pin against retraction when operatively engaged with the keeper member.

It is also an object of the invention to provide a latch mechanism particularly designed for use in connection with a sliding door and wherein the latch is constructed in a manner to provide means whereby the latch will automatically close when the door is moved into its closed position.

The invention consists in the details of construction and in the combination and arrangement of the several parts of my improved latch mechanism whereby certain important advantages are attained, as will be hereinafter more fully set forth.

In order that my invention may be better understood, I will now proceed to describe the same with reference to the accompanying drawing, wherein:

Figure 1 is a view in elevation illustrating a latch mechanism constructed in accordance with an embodiment of my invention, the associated door and wall being in fragment.

Figure 2 is a sectional view taken substantially on the line 2—2 of Figure 1.

Figure 3 is a sectional view taken substantially on the line 3—3 of Figure 1, the door being shown in full lines in partly opened position and indicated in fully closed position by broken lines.

Figure 4 is a sectional view taken substantially on the line 4—4 of Figure 1, and

Figure 5 is a view in elevation, with a portion broken away, of the bolt as herein embodied, unapplied.

As disclosed in the accompanying drawing, W denotes a wall, such as the side wall of a car, having the usual door opening O with which is associated a sliding door D. While this door D may be of any type desired, it is preferred to be substantially of the character of door comprised in my pending application Serial No. 453,747, filed August 5, 1942.

The forward or front portion of the door D at the required location thereon is provided with an outstanding staple 1 with which is freely en-

gaged a rearwardly disposed tail portion 2 carried by a latch pin 3 which is adapted to extend through an opening 4 of the keeper block 5.

This keeper block 5 is carried by an elongated plate 6 suitably anchored to the outer face of the wall W adjacent to the door opening O and in such position that when the pin 3 is substantially horizontal, said pin will enter the opening 4 during the period the door D is being brought into its fully closed position.

To facilitate the entrance of the pin 3 into the opening 4, the door D at a point below and forwardly of the staple 1 is provided with an outstanding lug 7 upon which the pin 3, or more particularly the tail-piece 2 thereof, rests. The pin 3 is provided therethrough with an opening 8 which is vertically directed when the pin 3 is disposed through the opening 4.

When the door D is fully closed, this opening 8 is in register with a vertically disposed opening 9 through the keeper block 5 and in which is slidably received the lower portion of the holding bolt 10. This bolt 10 is also slidably disposed through an outstanding flange 11 carried by the plate 6 and overlying the keeper block 5. Above the flange 11 and at a side of the plate 6 is an outstanding plate 12 provided in its upper face with a notch 14.

As clearly illustrated in Figures 1 and 3 of the drawing, this plate 12 is disposed inwardly in a direction transversely of the plate 6 or in a direction away from the door opening O on an angle of approximately 90 degrees and the notch 14 hereinbefore referred to is in relatively close proximity to the outer or free end of this plate 12.

When the bolt 10 is in its raised position so as to be free of the opening 4 of the keeper block 5, a laterally disposed arm 15 at the upper end of the bolt 10 is received within the notch 14 of the plate 12, whereby the bolt 10 is held in its raised position. However, when it is desired to have the bolt 10 drop down through the opening 8 in the pin 3, it is only necessary to raise the bolt 10 sufficiently to allow the arm 15 to be swung free of the plate 12. In order to prevent complete displacement of the bolt 10, the upper end of the plate 6 is provided with an outwardly disposed cap plate 16 extending in the same general direction as the flange 11 but spaced a sufficient distance thereabove to permit desired manipulation of the bolt 10.

The bolt 10, as is clearly illustrated in the accompanying drawing, is of a length to extend below the keeper block 5 when the bolt is in operative engagement with the pin 3 and said lower or

extended end portion is provided therethrough with an opening 17 to allow for the application of the conventional seal 18.

In connection with a sliding door, particularly of the type used on freight cars, it is of extreme importance that means be provided to permit an automatic release of the latch mechanism when the door D is closed. In the present embodiment of the invention, the door D has secured thereto, as at 19, a pin 20. This pin 20 extends slightly beyond the end of the door beyond the forward or front end of the door and is positioned slightly above the plate 12, so that the extended or free extremity of the pin 20 will contact the rounded portion 21 at the outer extremity of the arm 15 when said arm is resting within the notch 14 of the plate 12.

This contact of the pin 20 with the under rounded portion 21 of the arm 15 will raise the arm 15 out of the notch 14 and at the same time swing the arm 15 outwardly beyond and free of the plate 12 so that the bolt 10 will drop by gravity into its locking or holding engagement with the pin 3.

This action of the pin 20 upon the arm 15 is further facilitated by having the outer extremity of the pin 20 rounded, as at 22, said rounded portion being disposed inwardly and outwardly with respect to the pin 20 whereas the rounded portion 21 of the arm 15 is disposed in substantially the opposite direction when the arm 15 is at rest upon the plate or part 12.

It has also been found advantageous to have the bolt 10 slightly tapered or wedge-like so that when it is disposed through the opening 4 of the pin 3, it will have the effect of holding the door D more tightly closed.

It is also to be pointed out that the angular arrangement of the plate or part 12 assures the arm 15 passing out of the notch 14 under the action of the pin 20 as such particular arrangement of the plate or part 12 permits the bolt 10 to readily turn and not have a tendency to remain solid as would be the case if said plate or part 12 was substantially at right angles to the plate 6.

From the foregoing description it is thought to be obvious that a latch mechanism constructed in accordance with my invention is particularly well adapted for use by reason of the convenience and facility with which it may be assembled and operated.

What is claimed is:

1. Latching means for a closure member mounted for movement to opened or closed position relative to an opening, comprising a pin adapted to be shiftably supported by the closure member, a keeper member adapted to be mounted adjacent to the opening, said keeper member having an opening to receive the pin as the closure member is moved into closed position and the pin is in substantially a horizontal position, means coacting with the keeper member and the pin when engaged therewith to hold the pin against retraction, means for holding the said last named means free of the pin, and coacting parts adapted to be carried by the first named means and the closure member for releasing the first named means from its free position when the closure member is moved into substantially fully closed position.

2. Latching means for a closure member mounted for movement to opened or closed position relative to an opening, comprising a pin

adapted to be shiftably supported by the closure member, a keeper member adapted to be mounted adjacent to the opening, said keeper member having an opening to receive the pin as the closure member is moved into closed position and the pin is in substantially a horizontal position, a bolt freely moving through the keeper member from above and engageable with the pin to hold the pin against retraction, means for holding the bolt in a raised position free of the pin as it enters the keeper, and coacting means carried by the sliding closure member and the bolt for freeing said bolt from its holding means to permit the bolt to drop into holding engagement with the pin.

3. Latching means for a closure member mounted for movement to opened or closed position relative to an opening, comprising a pin adapted to be supported by the closure member, a keeper adapted to be mounted upon the wall adjacent to the opening, said keeper having an opening to receive the pin as said closure member is moved into closed position, a bolt supported above the keeper, said bolt being freely insertible by gravity through the keeper member to engage the pin to hold the pin against retraction, a laterally disposed arm carried by the bolt, a part adapted to be carried by the wall with which the arm of the bolt engages to hold the bolt in raised position free of the pin, and a part adapted to be carried by the closure member to engage the arm of the bolt when such arm is in engagement with the first part to free arm from the said first part as the closure member is moved into closed position to allow the bolt to drop by gravity into holding engagement with the pin.

4. Latching means for a closure member mounted for movement to opened or closed position relative to an opening, comprising a pin adapted to be mounted on the closure member, a keeper member adapted to be mounted upon the wall adjacent to the opening, said keeper member having an opening to receive the pin of the closure member as the closure member is moved into closed position, a bolt adapted to be supported by the wall for both endwise and rotary movement, said bolt freely extending into the keeper to engage the pin to hold the pin against retraction, a laterally disposed arm carried by the bolt, and a part adapted to be carried by the wall with which said arm of the bolt releasably engages upon turning movement of the bolt to hold the bolt in a position free of the pin as it enters the keeper.

5. Latching means for a closure member mounted for movement to opened or closed position relative to an opening, comprising, a pin adapted to be mounted on the closure member, a keeper member adapted to be mounted upon the wall adjacent to the opening, said keeper member having an opening to receive the pin of the closure member as the closure member is moved into closed position, a bolt adapted to be supported by the wall for both endwise and rotary movement, said bolt freely extending into the keeper to engage the pin to hold the pin against retraction, a laterally disposed arm carried by the bolt, a part adapted to be carried by the wall with which said arm of the bolt releasably engages upon turning movement of the bolt to hold the bolt in a position free of the pin as it enters the keeper, and means for automatically turning the bolt to release the arm from the part as the pin enters the keeper to permit the bolt to automatically move into holding engagement with the pin.

6. Latching means for a closure member mounted for movement to opened or closed position relative to an opening, comprising a plate adapted to be secured to the wall adjacent to the opening, an outstanding keeper block carried by the plate and having an opening therein, a pin adapted to be carried by the closure member and entering the opening of the keeper block as the closure member is moved into closed position, an outstanding flange carried by the plate above the keeper block, a bolt slidably and rotatably disposed through the flange and extending downwardly and freely through the keeper block to engage the pin to hold the pin against retraction, a laterally disposed arm carried by the bolt, and an outstanding part carried by the plate above the keeper block, the arm of the bolt engaging said part from above, said part being spaced a distance above the keeper block to hold the bolt raised free of the opening in the keeper block when the arm of the bolt is engaged with the part, said bolt when the arm is freed from the part, said bolt when the arm is freed from the part dropping by gravity into holding engagement with the part.

7. Latching means for a closure member mounted for movement to opened or closed position relative to an opening, comprising a plate adapted to be secured to the wall adjacent to the opening, an outstanding keeper block carried by the plate and having an opening therein, a pin adapted to be carried by the closure member and entering the opening of the keeper block as the closure member is moved into closed position, an outstanding flange carried by the plate above the keeper block, a bolt slidably and rotatably disposed through the flange and extending downwardly and freely through the keeper block to engage the pin to hold the pin against retraction, a laterally disposed arm carried by the bolt, an outstanding part carried by the plate above the keeper block, the arm of the bolt engaging said part from above, said part being spaced a

distance above the keeper block to hold the bolt raised free of the opening in the keeper block when the arm of the bolt is engaged with the part, said bolt when the arm is freed from the part dropping by gravity into holding engagement with the bolt, and a cap plate extending out from the first plate at a point above the part to limit the bolt in its upward movement, said cap plate being spaced a distance above the part sufficient to allow for unobstructed swinging movement of the arm of the bolt into or out of engagement with the part.

8. Latching means for a closure member mounted for movement to opened or closed position relative to an opening, comprising a pin adapted to be carried by the closure member, a keeper adapted to be mounted upon the wall adjacent to the opening, said keeper having an opening to receive the pin of said closure member as said closure member is moved into closed position, a bolt adapted to be supported by the wall above the keeper, said bolt being freely insertible by gravity through the keeper member to engage the pin to hold the pin against retraction, a laterally disposed arm carried by the bolt, a part adapted to be carried by the wall with which the arm of the bolt engages to hold the bolt in raised position free of the pin, and a part adapted to be carried by the closure member to engage the arm of the bolt when in engagement with the first part to free arm from the said first part as the closure member moves into closed position to allow the pin to drop by gravity into holding engagement with the bolt, said first part being provided in its top portion with a notch in which the arm of the bolt seats, said first part being angularly disposed in a direction away from the door opening to facilitate the release of the arm of the bolt from said first part under the action of the part carried by the closure member.

FRANK H. ROGERS.
